UNITED STATES PATENT OFFICE.

GEORGE H. FORSYTH, OF CHICAGO, ILLINOIS.

METAL WINDOW.

No. 914,651.

Specification of Letters Patent. Patented March 9, 1909.

Application filed April 5, 1905. Serial No. 253,928.

To all whom it may concern:

Be it known that I, GEORGE H. FORSYTH, a citizen of the United States, residing at Chicago, in the county of Cook and State of Illinois, have invented certain new and useful Improvements in Metal Windows, of which the following is a specification.

My invention has for its general object to provide an improved metal window construction wherein the sash may be adapted to variations in width or height of the casing, while at the same time preserving the proper engagement with the guides of the casing. I show constructions wherein this object may be accomplished through the provision of coöperating surfaces on the sash and guide inclined to the plane of the sash, and also by means of an adjustable element of the sash, the latter also permitting the edgewise insertion of the glass within the sash.

My invention, in an approved form, is illustrated in the accompanying drawings, wherein,—

Figure 1 is an elevational view of a window sash showing one of the stiles thereof removed to facilitate the edgewise insertion of the glass into the sash and illustrating the adjustability of one of the sash members. Fig. 2 is a top plan view, partly broken out and in section; Fig. 3 is a vertical sectional view on the line 3—3 of Fig. 1; Fig. 4 is a bottom plan view, partly broken out, of Fig. 1; Fig. 5 is a detail horizontal sectional view illustrating the means for adjustably uniting the detachable sash member to the sash frame; Fig. 6 is a detail elevational view of the lower right hand corner of the sash showing the detachable stile in the sash frame; Fig. 7 is a similar view of the upper right hand corner of the sash; Figs. 8 and 9 are detail cross-sectional views, on an enlarged scale, on the lines 8—8 and 9—9, respectively, of Fig. 7; and Figs. 10 to 19, inclusive are detail cross-sectional views illustrating the various forms of inclined surface engagement between the sash and its casing guides.

In the drawings, 20 designates as an entirety the bars and 21 the stiles of the sash. In the forms herein shown, these members are hollow, being made of suitably bent strips of sheet metal. As shown at the upper end of Fig. 3 the two parallel face members of the stile are inwardly offset at 22 to permit the offset portions to be overlapped by the ends of the parallel members of the bar 20

and riveted thereto, presenting flush surfaces on both sides. One of the stiles 21 (that shown at the right in Fig. 1) is removably and adjustably secured to the top and bottom bars by the following means. The upper and lower offset portions 22 of said stile are provided with holes 23 and 24, respectively, occupying varying transverse positions in the stile, said holes being adapted to register with holes 25 and 26 formed through the adjacent ends of the upper and lower bars, respectively, and receive screws or bolts 27 and 28 for uniting said members. An auxiliary means for adjustably securing the removable stile 21 may consist of a pair of spring tongues 29 (Fig. 5) secured to the inner faces of the parallel members of either or both of the bars, said tongues being inwardly offset to provide for the insertion of the offset end portions 22 of the stile between the same and the inner faces of the bars, and having outwardly turned lips 29^a adapted to enter in one vertical series of a number of correspondingly shaped slots 30 formed through the offset portions 22 of the stile. This auxiliary fastening means may be applied to either or both of the bars and either or both ends of the stile, as desired.

31 designates the glass, held in place within the sash by strips 32, preferably also of sheet metal and bent to the cross-sectional form indicated in Figs. 8 and 9, said strips having a hollow portion 32^a extending within the hollow stiles (for which purpose said stiles are bent to provide a reentrant portion 21^a, Figs. 8 and 9) and inwardly inclined spring lips 32^b clamping the glass. In order to insure a closed joint of the glass-holding strips at the corners formed by the removable stile, I miter the ends of the strip 32 carried by the removable stile, which provides an opening for the passage therethrough of the adjacent ends of the horizontal strips carried by the upper and lower bars, the mitered ends of the vertical strip 32 providing a closed joint with the inclined sides of the removable strips in all positions of adjustment, as more clearly shown in the cross-sectional view, Fig. 9.

From the foregoing it will be observed that in assembling the parts of the sash, before the removable stile 21 is applied the glass 31 can be inserted edgewise into position, Fig. 1 showing said glass inserted through the open edge of the sash and nearly in fully entered position therein. The re-

movable stile 21 is then applied, the upper and lower offset ends entering inside the adjacent ends of the bars and, in the case of the upper end as herein shown, fitting between 5 the latter and the spring tongues 29, as shown more particularly in Figs. 5 and 7. In this operation the lips 29^a enter one of the series of slots 30, according to the intended width over all of the sash, in which position 10 the hole 25 registers with one of the holes 23, the holes 26 in the lower bar similarly registering with a pair of holes 24, the exposed edge of the glass being received to a greater or less depth between the strips 32, as clearly 15 shown in Figs. 8 and 9. The insertion of the screws 27 then effects the secure union of the parts, preventing accidental displacement of the removable stile.

At the lower end of the stiles I have shown 20 the latter connected to the adjacent ends of the lower bar (see Fig. 3) by means of cleats 33 riveted to the inner sides of the parallel face members of said bar and stiles; this last described connection being optional with the 25 construction shown at the upper end of the stile for uniting the same parts.

It will be observed that the sash described and shown has merely stiles which are transversely yieldable or elastic, for which purpose 30 the solid transverse portion of the upper bar is cut away where it overlies the upper ends of the stiles, as shown at 34 in Fig. 2; and similarly the solid transverse member of the lower bar may be cut away at the ends 35 to form V-shaped openings 35, the gussets thus formed (for the sake of giving a more nearly closed and finished appearance) being severed from the intermediate portion of the transverse member, as indicated at 35^a, this 40 construction permitting transverse yielding or elasticity at the lower ends of the stiles.

In Figs. 10 to 19, inclusive, I have illustrated a variety of forms which the coöperating stiles and guides of the casing may 45 assume, all with the general purpose of permitting a certain extent of bodily widthwise adjustment of the sash relatively to the opening while maintaining a proper fit of the stiles in or upon their guides. It will be 50 observed as a characteristic common to all of these forms that the sash member and guide have coöperating surfaces that are inclined or oblique to the plane of the sash, this construction, where the sash member is 55 transversely yieldable or elastic, permitting widthwise variation of the sash relatively to the opening without destroying the proper engagement of the sash and guide. In all of the figures except Fig. 19, 36 may be 60 assumed to represent in cross-section a portion of the casing having a vertical guide-groove 37. In Fig. 10 I bend inwardly the projecting portion of one of the parallel face members of the stile, as shown at 38, said 65 bent margin contacting a strip 39 secured to

the casing as by a screw 40 having a beveled or oblique sash-engaging surface 39^a.

In Fig. 11 the groove 37 is obliquely undercut on one side, providing an inclined surface 37^a engaged by an outwardly bent margin 41 70 of one of the parallel face members of the stile, the other face member being straight and engaging the straight side of a removable strip 42.

In Fig. 12 both of the parallel face members of the stile are outwardly bent marginally as shown at 41, and the strip 42 of Fig. 11 is replaced by a strip 43 similar thereto except that it has an oblique inner bearing surface 43^a engaging one of said bent margins 41. 75

In Fig. 13 the groove 37 has both its side walls inclined in the same direction (herein shown as parallel), as indicated at 44; and the marginal portions of the face members of 85 the stile are similarly bent or inclined to fit said surface.

In Fig. 14 the integral side wall of the groove is inclined inwardly relatively to the sash from its outer edge, as indicated at 45, 90 the coöperating margin of the stile being similarly bent to engage the same; while the inwardly turned margin of the other face member of the stile engages a wear strip 46 secured in place as by a screw or brad 47 and 95 having a wear face 48 similarly but oppositely inclined to the wall 45. Said wear strip 46 is backed by a finishing strip 49 extending flush with the inner transverse wall of the casing opening. 100

Fig. 15 shows a stile having one straight face and its other face outwardly bent marginally to engage a correspondingly inclined surface 50^a of a removable strip 50.

Fig. 16 shows a casing provided with a 105 substantially V-shaped groove, and the marginal portions of both face members of the stile inwardly turned to engage the inclined walls 51 of said V-groove.

In Fig. 17 I have shown the bottom wall 110 of the groove provided with a central projecting rib 52 having oppositely inclined surfaces 52^a that are engaged by inwardly and backwardly bent marginal portions 53 of the parallel face members of the stile, the latter 115 having also an outside bearing against the parallel side walls of the groove.

Fig. 18 shows one side wall of the groove formed by a removable strip 54, the inner face of said strip having a straight portion 120 54^a engaging one of the parallel face members of the stile, and also an inclined convex portion 54^b which is adapted to be engaged by an inwardly turned marginal portion 55 of the other face member of the stile. 125

The principle of the oblique or inclined transversely adjustable bearing between the sash and the guide, as exemplified in Figs. 10 to 18, inclusive, is capable of being carried out in constructions wherein the acting guide, 130

instead of being formed as a groove, takes the form of a rib or projection embraced by the parallel face members of the stile. Such a construction is shown in Fig. 19, wherein 5 56 designates a guide rib triangular in cross-section secured to the wall 36 of the casing as by a screw 57, the opposite inclined sides of said strip being slidably engaged by inwardly bent inclined marginal portions 58 of the 10 stile members.

In the forms shown in Figs. 10 to 18, inclusive, wherein the sash guide consists of a groove in the casing, the parallel face members of the stile may possess a transverse elasticity normally tending to spread said members beyond the width of the groove; in 15 which case said members, when engaged in the groove, are under a greater or less degree of compression, thus insuring a dust-proof 20 and rattle-proof fit. At the same time the provision of the inclined engaging surfaces combined with the elasticity of the sash member enables a given sash to fit and operate in window openings of somewhat varying 25 widths. On the other hand, where the sash member may not possess transverse elasticity, as when made solid, the same adaptability of the sash to window openings of somewhat varying widths is secured by 30 the detachable strips which may, after the sash has been introduced, be applied so as to produce an operative fit against that side of the sash which they engage. In the case of the construction shown in Fig. 14 the inner 35 strip 46 may be adjusted within certain limits without disturbing the position of the main confining strip 49.

The constructions hereinabove described may lend themselves to a still further advancement in respect to the manner of inserting the sash in the casing where the total width of 40 the sash is less than the distance between the bottoms of the grooves by a distance equal to or greater than the depth of one of the 45 grooves, in which case, by sufficiently expanding or contracting the stile on one side it may be inserted into one of the grooves until contacting the bottom of the latter, which will allow the outer margin of the other stile 50 to enter the mouth of its coöperating groove, the sash being then moved widthwise of its groove. Such a construction is illustrated in Figs. 15 and 16.

I do not limit the invention to the particular forms and constructions shown and described, as the same may obviously be varied to a considerable extent without departing from the principle of the invention or sacrificing any of the advantages thereof.

60 I claim:

1. A sash having an adjustable frame member adapted to accommodate the sash to varying sizes of opening, substantially as described.

2. A sash having an adjustable stile 65 adapted to accommodate the sash to varying widths of opening, substantially as described.

3. A sash having a removable and adjustable frame member adapted to permit the edgewise insertion of the glass into the sash 70 and adapting the latter to varying sizes of opening, substantially as described.

4. A sash having a removable and adjustable stile adapted to permit the edgewise insertion of the glass into the sash and adapting the latter to varying widths of opening, 75 substantially as described.

5. A hollow metal sash having an adjustable frame member adapted to accommodate the sash to varying sizes of opening, substantially 80 as described.

6. A hollow metal sash having an adjustable stile adapted to accommodate the sash to varying widths of opening, substantially 85 as described.

7. A hollow metal sash having a removable and adjustable frame member adapted to permit the edgewise insertion of the glass into the sash and adapting the latter to varying 90 sizes of opening, substantially as described.

8. A hollow metal sash having a removable and adjustable stile adapted to permit the edgewise insertion of the glass into the sash and adapting the latter to varying 95 widths of opening, substantially as described.

9. A hollow metal sash having a removable and adjustable stile, wherein the ends of the removable stile and the coöperating ends of the bars are provided, the one with a series of transversely separated apertures and the other with an aperture adapted to register with any one of said series and to receive a securing pin or bolt, substantially as described.

10. A hollow metal sash having a removable and adjustable stile, wherein the ends of the removable stile are provided with a series of transversely separated apertures, and the coöperating ends of the bars are provided with an aperture adapted to register with any one of said series and to receive a securing pin or bolt, substantially as described.

11. A hollow metal sash comprising in combination with a bar thereof, a pair of 115 spring tongues having inwardly turned lips secured to the parallel face members of said bar near its end, and a removable stile having a series of transversely disposed apertures formed through its parallel face members, the apertured ends of said face members of the stile lying between the face members of the bar and said tongues with the lips of the latter engaging one of said series of apertures, substantially as described.

12. A metal sash having a hollow laterally adjustable stile, said stile being provided with a hollow glass-engaging strip having

mitered ends adapted to be entered by the adjacent ends of the glass-holding strips carried by the bars, substantially as described.

13. The combination with a metal sash 5 having an adjustable element carried thereby provided with a surface inclined to the plane of the sash, of a sash guide adapted to engage said inclined surface whereby to adapt the sash to varying widths of sash 10 opening, substantially as described.

14. The combination with a metal sash having an adjustable elastic element carried thereby, of a sash guide having a surface inclined to the plane of the sash and adapted 15 to be engaged by said elastic element of the sash whereby to adapt the latter to varying widths of sash opening, substantially as described.

15. The combination with a metal sash 20 having an adjustable elastic element carried thereby provided with a surface inclined to the plane of the sash, of a sash guide having a surface inclined to the plane of the sash and engaging 25 said elastic element of the latter whereby to adapt the sash to varying widths of sash opening, substantially as described.

16. The combination with a sash having 30 an adjustable transversely elastic stile provided with a surface inclined to the plane of the sash, of a sash guide adapted to engage 35 said inclined surface whereby to adapt the sash to varying widths of sash opening, substantially as described.

17. The combination with a sash having 35 an adjustable transversely elastic stile, of a sash guide having a surface inclined to the plane of the sash engaged by said stile, whereby to adapt the sash to varying widths of sash opening, substantially as described.

40 18. The combination with a sash having an adjustable transversely elastic stile provided with a surface inclined to the plane of the sash, of a sash guide having a surface inclined to the plane of the sash and engaging 45 said inclined surface of the latter whereby to adapt the sash to varying widths of sash opening, substantially as described.

19. The combination with a casing guide having a surface inclined to the plane of the 50 sash, of a sash having a stile provided with an inclined surface elastically engaging said inclined surface of the guide, substantially as described.

20. The combination with a casing guide 55 having a detachable element, of a sash having a transversely elastic stile provided with an inclined surface engaging said guide, substantially as described.

21. The combination with a casing guide 60 having a detachable element and an inclined surface, of a sash having a transversely elastic stile engaging said guide, substantially as described.

22. The combination with a casing guide 65 having a detachable element and an inclined

surface, of a sash having a transversely elastic stile provided with an inclined surface engaging the inclined surface of said guide, substantially as described.

23. The combination with a casing guide 70 having a detachable element, of a sash having a transversely elastic stile provided with an inclined surface engaging said detachable element, substantially as described.

24. The combination with a casing guide 75 having a detachable element provided with an inclined surface, of a sash having a transversely elastic stile engaging said inclined surface of said detachable element, substantially as described.

25. The combination with a casing guide having a detachable element provided with an inclined surface, of a sash having a transversely elastic stile provided with an inclined 80 surface engaging the inclined surface of said detachable element, substantially as described.

26. The combination with a casing guide having a finishing strip and an adjustable 85 guide element, of a transversely elastic stile 90 engaging said guide, substantially as described.

27. The combination with a casing guide having a finishing strip and an adjustable 95 guide element provided with an inclined surface, of a transversely elastic stile engaging 100 said inclined surface of said guide element, substantially as described.

28. The combination with a casing guide having a finishing strip and an adjustable 10 guide element provided with an inclined surface, of a transversely elastic stile having an inclined surface engaging the inclined surface of said guide element, substantially as described.

29. A metal sash having a relatively movable stile and bar, one of said members being provided with an element adapted to adjustably engage and secure the other, substantially as described.

30. The combination with a casing having a guide permitting transverse yielding of a sash frame-member engaged therewith, of a metal sash having hollow frame-members one of which engages said guide, one of said sash frame-members having the ends of its sides offset and overlapped by the ends of the sides of an intersecting sash frame-member whereby to prevent flush surfaces at the corner of the sash, substantially as described.

31. The combination with a casing having a guide permitting transverse yielding of a sash stile engaged therewith, of a metal sash having a bar and a hollow stile engaging said guide, said stile having the ends of its sides offset and overlapped by the intersecting end of the bar whereby to prevent flush surfaces at the corner of the sash, substantially as described.

32. The combination with a sash guide 13

permitting transverse yielding of a sash frame-member when engaged therewith, of a metal sash having a transversely elastic frame-member provided with an inclined surface engaging said sash-guide, substantially as described.

33. The combination with a sash guide permitting transverse yielding of a sash stile when engaged therewith, of a metal sash having a transversely elastic stile provided with an inclined surface engaging said sash guide, substantially as described.

34. The combination with a sash having a transversely elastic stile, of a sash guide having a surface inclined to the plane of the sash and permitting transverse yielding of the stile, substantially as described.

35. The combination with a sash having a transversely elastic stile provided with an

inclined guide-engaging surface, of a sash 20 guide having a surface inclined to the plane of the sash and engaging said inclined surface of the latter, said sash guide permitting transverse yielding of the stile, substantially as described.

36. The combination with a casing strip having a sash guide groove formed with vertical and inclined walls, of a hollow sash frame-member the sides whereof engage the vertical walls of the guide grooves and are 30 provided with inclined flanges engaging the inclined walls of the guide, substantially as described.
